(57)

CLAIM

The ornamental design for a laser marking machine, as shown and described.

DESCRIPTION

1. Laser marking machine

1.1 : Perspective

1.2 : Front

1.3 : Back

1.4 : Top

1.5 : Bottom

1.6 : Left

1.7 : Right

1.8 : Perspective view showing the Laser Marking Machine in a state of use when the cover is open.

The broken lines are shown for the purpose of illustrating portions of the laser marking machine that form no part of the claimed design.

1 Claim, 8 Drawing Sheets(56)
